Charles Feuner, of Cincinnati, Ohio
Assignor

M. Greenwood & Co. of same place.

Letters Patent No. 3364 - Dated July 13, 1866.

Design for a Piano Stool.

The schedule referred to in these Letters Patent and making part of the same.

Stall whom it may concern:

Bent knoweth that I, Charles Feuner, of Cincinnati, in the County of Hamilton and State of Ohio, have invented a new and original ornamental design for a Piano Stool, and I hereby declare that the same clearly and fully represented in the accompanying drawings, which are made a part of this specification, and in which

Fig. 1 an elevation of the entire stool, and

Fig. 2 a front elevation of one of the feet thereof.

I claim as my invention and desire to have secured to me by Letters Patent

The design for a Piano Stool, herein represented and described.

In testimony of which invention, I, herunter by hand,

Witness,

Geo. W. Knight.
